UNITED STATES PATENT OFFICE

LEON E. KLEIN, OF LOS ANGELES, CALIFORNIA

WEATHER GUARD FOR CASEMENT WINDOWS

Application filed April 30, 1928. Serial No. 273,791.

This invention relates to closures for windows and the like and more particularly to weather strips for sealing windows of the casement type, which as is well understood are hinged to the window frame at one side.

Heretofore it has been common to swing casement windows outward in order that, when closed, the window could co-operate with the sill to form a proper guard for excluding wind and rain. Where such windows were hung to swing inward a satisfactory seal was rarely if ever produced.

The primary object of the present invention is to provide a guard for windows, which guard is especially adapted to be used with windows hung to swing inward and which at the same time will serve effectually to exclude the weather. A further object is to provide such a guard which will be automatically actuatable to and from operative position as the window is closed and opened.

Stated briefly, the invention resides in the combination of a window frame having a sill and a window sash hinged to the frame at one side, with a guard rail mounted on the sill and adapted to enter a groove extending longitudinally in the lower edge of the bottom bar of the sash, the groove in the bar being wider near the hinged edge of the sash than at the free end in order that sufficient clearance will be provided to avoid premature actuation of the guard rail by permitting the sash to be moved almost to closed position before engagement of said rail by the free or outer end of the groove wall causing the rail to be urged toward operative or upright sealing position. The under edge of the outer side of the bar forming the groove is slightly tapered at the end on the hinged side for the purpose of insuring depression of the rail and avoid jamming when the window starts to swing to closed position. The invention also resides in such other novel features of construction and arrangement as may be herein presented.

In the accompanying drawings wherein one form of the invention is disclosed by way of illustration;

Fig. 1, is an inside elevation of a window frame in which are hung two casement win-

dows constructed to co-operate respectively with two weather guards according to this improvement, the windows being shown in open position and the guards in corresponding or lowered position.

Fig. 2, is partially a horizontal section and partially a plan as viewed from the line 2—2 of Fig. 1.

Fig. 3, is a vertical section taken from line 3—3 of Fig. 1.

Fig. 4, is chiefly an elevation of the structure of Fig. 1, the windows being closed.

Figs. 5 and 6, are fragmentary sections taken respectively on the lines 5—5 and 6—6 of Fig. 4, showing the relation of the guard rail to the groove at the outer and inner ends thereof respectively, when the window is closed; in Fig. 6, the position of the guard rail in the inner end of the groove just before commencing the last portion of the closing operation, is indicated in dotted lines.

Fig. 7, is a similar view taken at the position of the line 5—5 showing the relation of the guard rail and the outer end of the groove just when the window is in position to commence to move the guard rail to upright or closed position, this closed position being represented in dotted lines and corresponding to the position shown in Fig. 5.

Fig. 8 is a fragmentary horizontal section taken on line 8—8 of Fig. 4, the window being closed.

According to these drawings, a window frame 10 having an outer sill 12 and an inner sill 14, is provided with two casement windows whose sashes 15 are hinged thereto at 16, the lower bar of each sash co-operating with a movable guard rail 20 hinged at 22 to the outer edge of the outer sloping portion 14' of the sill 14, swinging movement of the rail being permitted by beveling the under side at 23. Each lower sash bar 15 is provided on its under side with a longitudinally extending groove 24 which forms an outwardly facing vertical wall 25 lying alongside the rail 20 when in operative position. However, the outer portion of the bar 15 opposite said wall 25 and on the outer side of the groove is largely cut away in the form shown leaving only a depending narrow lip

26 whose under edge preferably is beveled transversely at 27 to co-operate with a correspondingly beveled face on the rail 20 for proper exclusion of rain and the like. Thus, 5 there is formed on the rail an upstanding tongue 30 extending longitudinally thereof and normally disposed in said groove 24.

It is to be noted particularly that, since the inner end of each bar 15 (that end near 10 the hinged side of the sash) moves almost to closed position much earlier in the closing movement than does the outer or free end of the bar, the inner end of the groove 24 must be formed so as not to actuate the guard rail 20 before the outer end of the bar has nearly reached closed position. Otherwise, 15 the wall 25 of said groove would begin to swing the rail 20 into closed position before its entire length could enter the groove, in which case the upper edge of the rail would 20 jam against the lower edge of the lip 26. Therefore it is necessary that the inner end of the groove be wider with respect to the thickness of the rail than the outer end and that this extra width be sufficient to accommodate the differential of movement. This is 25 accomplished by extending the wall 25 of said groove at an angle as best seen in Figs. 2 and 8, whereby the groove is tapered and gradually widens, the outer wall of the groove 30 forming the inner face of lip 26 being parallel with the outer walls of the bar.

The relation of these parts in various positions is illustrated best in Figs. 5, 6 and 7, 35 wherein Fig. 5, shows the relation of the parts at the outer end of the rail and groove, the parts being in closed or operative position. In Fig. 6, the relation of the parts in the same position at the outer end of the groove 40 is shown in full lines, while the position of the rail 20 in the groove just before the rail commences to move to closed position is shown in dotted lines. In Fig. 7, there is shown in full lines the position of the parts at the 45 outer end just before the wall 25 engages and commences to swing the rail, the closed position (that of Fig. 5) being indicated in dotted lines.

Thus it will be seen that, as the window is 50 swung toward closed position, the rail being in open or dropped position as in Figs. 3 and 7, the lip 26 at the inner end passes over the rail and the extra width of the groove 24 at said inner end prevents engagement of the 55 wall 25 with the rail until the outer end of the wall 25 has reached the full-line position of Fig. 7, whereupon said wall 25 then causes the rail to swing upward and outward from the position of Fig. 7, and to pass into the 60 groove and thus into sealing position as seen in Figs. 5 and 6. In order that depression of the rail 20 into the open position of Figs. 1, 3 and 7, may be insured to avoid binding or jamming of the parts, the under edges of 65 the inner end of lip 26 is slightly beveled up-

ward at 26' as indicated in Fig. 1, this bevel first passing over the upper edge of the inner end of the rail, and, if the same is up a little too far, forcing the rail downward so that the rest of the under edge of said lip may pass freely along and over the upper edge of the rail.

The parts now being in the closed position, an effective weather seal is provided, the shedding of rain and the like being insured by the beveled faces 27 and 28 and also by the under beveled face 23, and wind and dust being excluded by the generally tight joints between the parts. Obviously, the thickness of the rail may be varied by tapering the same, the width of the groove being uniform, or both rail and groove may be tapered, either of these variations providing the required play at the inner end of the groove and rail.

I claim:

1. In combination, a swinging casement window having a transverse bottom bar, a sill co-operating therewith, and a transverse rail hinged to said sill, said bar having a longitudinally extending groove adapted to receive said rail as the window is swung to closed position, one end of the groove being wider than the other.

2. In combination, a window frame having a sill at its lower end, a window sash hinged to one side of said frame and having a lower bar, a transverse rail swingingly mounted on said sill and having an upstanding lip, said bar having a longitudinally extending groove in its lower edge to receive said lip, the width of said groove with relation to said lip being greater at the mounted side of the sash than at the free side, and a flange depending from said bar and extending below the upper edge of said lip regardless of the position of the rail, whereby said flange will engage and swing the rail into operative position.

3. A structure according to claim 1, wherein in the lower edge of the portion of the bar which passes over the rail is beveled upwardly at the end next to the mounted side of the sash in order to insure depression of the rail as the sash swings to closed position.

4. In combination, a window frame having a sill, a casement window sash hinged to one side of the frame, a weather guard hinged to said sill and extending therealong, the bottom of the sash having a groove in the bottom face thereof to receive the guard, the relative width of the groove with respect to the thickness of the guard gradually increasing from the outer end to the end at the hinged side.

In testimony whereof I affix my signature.

LEON E. KLEIN.
